I. CHASE

DOOR MOUNTING

Filed May 16, 1924.

UNITED STATES PATENT OFFICE.

IRWIN CHASE, OF BAYONNE, NEW JERSEY, ASSIGNOR TO THE ELCO WORKS OF THE ELECTRIC BOAT COMPANY, A CORPORATION OF NEW JERSEY.

DOOR MOUNTING.

Application filed May 16, 1924. Serial No. 713,837.

To all whom it may concern:

Be it known that I, IRWIN CHASE, a citizen of the United States, residing at Bayonne, in the county of Hudson, State of New Jersey, have invented certain new and useful Improvements in Door Mountings; and I do hereby declare the following to be a full, clear, and exact description of the invention, such as will enable others skilled in the art to which it appertains to make and use the same.

This invention relates to door mountings, the particular object of the invention being to provide a mounting for a door of ordinary construction which will permit the door to be opened wide without having the door project away from the door casing any considerable distance as the door is swung open.

This invention can be used for many purposes, although it was devised for use in connection with pleasure cruisers of the type having a deck house.

I prefer to describe my invention as used on a pleasure cruiser of this type, inasmuch as it has been found to be particularly useful in this connection.

A pleasure cruiser of the type above referred to includes a deck-house, the floor of which is substantially flush with the deck of the boat. It is desirable to provide as much space as possible within the deck-house, and accordingly the deck-house structure is made to extend out on each side of the boat so as to leave only a small side deck on each side thereof. The side deck, while large enough to permit one to walk along the side of the deck-house, is usually somewhat narrower than an ordinary doorway, and accordingly, if a door were provided in the side of the deck-house, hinged to its casing in the ordinary manner, it would not swing past the railing at the edge of the deck. This would be quite objectionable, for it would make it necessary to close the deck-house door whenever it was necessary to walk along the side deck past the door. It is not desirable to have the door swing in to the deck-house, for the space within the deck-house near the door can be used for many purposes of greater importance than merely to provide room for the door to swing in and against the inside of the deck-house wall. If a sliding door were provided, this would necessitate the construction of a door casing within the deck-house wall, and

this is objectionable for the reason that it is expensive to so construct a door casing, and whenever the door supports or the enclosed door casing would get out of order, it would be necessary to tear down part of the cabin wall in order to gain access to the disarranged or broken parts. A folding door is open to many of the objections noted in connection with the sliding door construction, by virtue of the large number of supporting parts which easily get out of order. Furthermore, an ordinary folding door would project out into the side deck a considerable distance whenever it was opened wide, and therefore it would probably be necessary to close even a folding door before one could get past the door along the side deck.

I have found that it is possible to provide a door mounting which is free from all the objections which prohibit the use of the several types of doors above described. In general, I accomplish this result by providing what may be called extension hinges fastened to the back edge of a door of ordinary construction. These hinges have pivot points on the door and on a hinge support which may well be the wall of the deck-house. A link extends between the pivot points on the deck-house wall and on the door. The length of this link is somewhat less than the width of the door and preferably of a length substantially equal to one-half the width of the deck-house door. By employing this type of door mounting, the back edge of the door is swung out toward the deck railing and then back against the side of the deck-house wall and it is not necessary for the front edge of the door to swing out away from the door casing at all. A unitary deck-house door of ordinary construction can therefore be used and the door can be opened wide without having the door project out so as to strike the deck railing when the door is open.

A feature of my invention which can be omitted if desired, but which is very useful in the event that a lock is to be provided on the door, comprises means for causing the front edge of the door to follow a certain path when the door is being swung open. Such a means may comprise lugs carried at the top and bottom of the door near the front edge thereof and cooperating with slots formed in the top and bottom of the

door casing. The lugs on the door cause the front edge thereof to follow a path corresponding with the slots in the door casing. An ordinary door lock can be provided at the back edge of the door, and this lock, together with the lugs and slots just referred to, prevent the door from being opened until the door lock is released or unlocked in the ordinary manner.

10 The various objects and advantages of my invention will be apparent upon considering the following detailed description, which is to be taken in conjunction with the accompanying drawings, in which—

15 Fig. 1 is a fragmentary perspective view of a portion of a pleasure cruiser of the type above described showing my improved door mounting applied thereto.

Fig. 2 is a horizontal section view of a portion of the deck-house and door of Fig. 1, showing the construction and operation of my invention.

Fig. 3 is an elevation of a door mounted in accordance with my invention; and

25 Fig. 4 is a vertical section taken on line 4—4 of Fig. 3, showing certain details of construction.

The pleasure cruiser of which Fig. 1 is a fragmentary view, comprises a deck-house located amidships and constructed so as to provide a narrow side deck on each side thereof. In Fig. 1, the deck-house wall is shown as 1, and the narrow starboard deck is shown as 2, and the usual deck-rail is shown as 3.

35 This pleasure cruiser is preferably about 56 feet in length, in which case the deck-house is approximately 15 feet long and completely encloses the bridge. The deck-house wall is provided with a large number 40 of windows, 4, so that when the weather is pleasant the deck-house can be opened completely. A door is provided on each side of the deck-house, opening out on to the side deck. One of these doors is shown at 5 in

45 Fig. 1.

It will be readily appreciated that in constructing a deck-house on a cruiser of this type there are many reasons why an ordinary door hinged in the usual manner cannot be used. By referring to Figs. 1 and 2, it will be noted that the width of the side deck 2 is only slightly greater than one-half the width of the door 5. Accordingly, if the door 5 were hinged in the ordinary manner so as to swing out, it would strike the deck rail 3 as soon as the door had been swung to an angle of about 40 or 45 degrees, and it would be impossible to walk along the side deck until the door was closed. If the door 60 were mounted so as to swing into the deck-house, it would strike against the deck seats just within the deck-house wall or against other objects which must be placed in close proximity to the doorways.

65 The preferred embodiment of my invention

includes two or more extension hinges designated generally by the reference characters 6 and 7. The hinge 6 includes a piece 8 adapted to be fixed to a support such as the deck-house wall and a second piece 9 adapted to be fixed to the upper back corner of the door 5. A link 10 connects these two pieces and is pivoted on each of them. The piece 9 projects up above the door so that the link 10 pivoted thereto clears the upper back corner of the door.

In like manner, the lower hinge 7 includes pieces 8' and 9', identical with the pieces 8 and 9 just described. The hinged pieces 8 and 9 are fixed to the wall and door respectively by any convenient means such as screws passing through holes in the pieces; and the pieces 8' and 9' are fastened in like manner. The hinge piece 9' projects down below the lower edge of the door and the link 10', which connects the pieces 8' and 9', clears the lower back corner of the door 5 in the same manner that the link 10 clears the upper back corner.

The door is opened by causing the back thereof to swing out as shown in Figs. 1 and 2, and the length of the links 10 and 10' determine the distance to which the back edge of the door will swing out away from the wall of the deck-house. The outer ends of the links 10 and 10' swing around in arcs of circles, the radii of which are equal to the distance between the points on which these links are pivoted; and the back edge of the door is carried around in a corresponding arc.

If the links 10 and 10' have a length equal to substantially one half the width of the door 5 the back edge of the door will be carried back a distance equal to substantially the width of the door, thus opening the door wide. This is the preferred manner in which to construct the links 10 and 10' although it is of course possible to make a satisfactory door mounting of this type by employing links of other lengths.

In Fig. 2, three positions of the door 5 are shown. The full line position is the position occupied by the door when it is closed in which case the links 10 and 10' are substantially parallel to the wall 1 of the cabin. It is desirable to have the hinge pieces 9 and 9' project out from the face of the door somewhat further than do the corresponding hinge pieces 8 and 8' so as to make the links 10 and 10' extend at a slight angle to the wall 1 substantially as shown. If the links 10 and 10' are exactly parallel with the wall 1 when the door is closed, the links are in substantially dead center positions and it is necessary to pull out on the back edge of the door in order to make the door open. By having the links set at a slight angle as just described it is not necessary to pull out on the links or on the back edge of the door

in order to make the door open, it being merely necessary to push back on the door knob.

If the links 10 and 10' are made longer than those shown in the figures of the drawing the door 5 will be carried back further than is necessary to expose all of the doorway, but as pointed out above, this may be desirable in some cases. On the other hand, 10 if the links are substantially shorter than those shown in the drawing the door will not be entirely drawn away from the door casing when the extension hinges are swung all the way back against the deck house 15 wall.

The features of my invention above described can be employed to advantage by themselves, but I prefer to add certain additional features which make the door mounting 20 of greater value for most purposes. The principal additional means which I prefer to use comprises means for causing the front edge of the door to follow a certain predetermined path when the door is swung open 25 on its extension hinges. This means may be in the form of lugs carried by the door and cooperating with slots whereby the front edge of the door is caused to follow a certain path.

30 In the figures of the drawing I have shown the door casing 11 as provided with slots at the top and bottom thereof, these slots extending from a point near the inner face of the door casing at the front edge of the casing 35 to a point near the outer face of the casing at the back edge of this casing. The door 5 is provided with two brackets 12 and 12' carrying lugs 13 and 13' which project into the grooves or slots in the door casing. 40 The brackets 12 and 12' can be fastened to the door in any convenient manner as by means of the screws 14. While it is true that the brackets 12 and 12' carrying the lugs 13 and 13' can be fastened to the door 45 at any point which will permit the lugs to cooperate with the grooves in the door casing, yet I prefer to mount these brackets at the upper and lower corners of the door opposite the back edge of the door. The 50 brackets and the slots in the door casing are constructed so that when the door is closed it is substantially flush with the cabin wall 1 and when the door is open it is substantially parallel with the cabin wall 1 as represented by the dot and dash line in Fig. 2. The dotted lines in Fig. 2 indicate a position 55 of the door intermediate its closed and wide open positions.

60 It is apparent that by providing extensions on the door casing at the top and bottom thereof the slots therein can be so formed that the door 5 would move parallel to itself when it was swung open, and in fact the slots can be shaped so that the 65 front edge of the door will follow any de-

sired path when the door is swung open. Regardless of the manner in which the slots are formed, it is obvious that they serve as an effective means for holding the front edge of the door in position when the door 70 is closed.

If it is desired to lock the door 5, it is merely necessary to provide a lock 15 of ordinary construction near the back edge of the door and this lock together with the 75 lugs 13 and 13' within the grooves in the door casing will prevent the door from being opened until the lock is released.

The door casing 11 may be an ordinary wooden door casing having slots cut in the 80 top and bottom portions thereof for the purpose described or the top and bottom parts of the casing may be of special construction. It may be desirable in order to prevent excessive wearing along the edges of 85 the slots or grooves of the door casing to provide metal plates 16 and 16' as shown in Figure 4 covering the face of the top and bottom portions of the door casing.

It is to be understood that many of the 90 details of construction of my invention may be modified without departing from the spirit of the invention which is not limited to the particular embodiment illustrated and described, but includes such modifications 95 thereof as fall within the scope of the appended claims.

I claim:

1. The combination of a door, a support 100 and means carried by the support and connected to one edge of the door for causing this edge of the door to swing out away from the support a maximum distance equal to approximately one half the width of the door and then back against the support 105 whereby the door is opened wide.

2. The combination of a door, a support, means carried by the support and connected to one edge of the door for causing this edge of the door to swing out away from the support a maximum distance equal to approximately one half the width of the door, and means other than the means carried by the support for causing the opposite edge of the door to follow a certain path when the 115 door is swung open.

3. The combination of a door, a support, means carried by the support connected to one edge of the door for causing this edge of the door to swing out away from the support a maximum distance equal to approximately one half the width of the door and means including lugs carried by the door for causing the opposite edge of the door to follow a certain path when the door is 120 swung open.

4. The combination of a door, a support, means carried by the support and connected to one edge of the door for causing this edge of the door to swing out away from the sup- 130

port a maximum distance equal to approximately one half the width of the door and means including a lug carried by the door near the other edge thereof and adapted to 5 cooperate with a slot to cause this other edge to follow a certain path when the door is swung open.

5. The combination of a door, a casing for said door, the said casing having a slot 10 therein, a support, means carried by said support and connected to one edge of said door for causing this edge to swing out away from the support when the door is opened and means carried by said door near 15 the other edge thereof and cooperating with the slot in the door casing to cause this other edge to follow a certain path corresponding to the slot when the door is opened.

6. The combination of a door, a door casing having a slot in the top thereof and a second slot in the bottom thereof, a support, means carried by the support and connected to one edge of the door for causing this edge to swing out away from the door casing 25 when the door is opened and lugs carried by the door at the upper and lower corners thereof opposite this edge of the door, the said lugs projecting into the slots in the door casing.

30 7. The combination of a door, a door casing having a slot in the top thereof and a second slot in the bottom thereof, the said slots extending from a point near the inner face of the door casing at one side thereof 35 to points near the outer face of the casing at the opposite side thereof, a support, means carried by the support and connected to one edge of the door for causing this edge to swing out away from the door casing 40 when the door is opened and lugs carried by the door at the upper and lower corners thereof opposite this edge of the door, the said lugs projecting into the slots in the door casing.

45 8. The combination of a door, a casing for said door, said casing having a slot therein extending to a point near the face of the casing at one edge of door, a support, means carried by said support and connected to 50 one edge of said door for causing this edge to swing out away from the support when the door is opened and means carried by said door near the other edge thereof and cooperating with the slot in the door casing 55 to cause this other edge to follow a certain path corresponding to the slot when the door is opened.

9. The combination of a door, a casing for said door, the said casing having a slot 60 therein, a support, means carried by said support and connected to one edge of said door for causing this edge to swing out away from the support when the door is opened and means carried by said door near the other edge thereof and cooperating with the

slot in the door casing to cause this other edge to follow a certain path corresponding to the slot when the door is opened, this last named means comprising a bracket fastened to the door and having a lug thereon projecting into the slot in the door casing. 70

10. The combination of a door, a door casing having a slot in the top thereof and a second slot in the bottom therof, a support, means carried by the support and connected to one edge of the door for causing this edge to swing out away from the door casing when the door is opened and brackets fixed to the door at the upper and lower corners thereof opposite this edge of the 80 door, the said brackets having lugs thereon projecting into the slots on the door casing. 75

11. The combination of a door, a support, a hinge piece fixed to said support, a second hinge piece fixed to one edge of the door 85 and a link connecting these hinge pieces, the length of this link being equal to substantially one half the width of the door.

12. The combination of a door, a support, hinge pieces fixed to the support, a hinge piece fixed to one edge of the door so as to project above the top of the door, a hinge piece fixed to the opposite edge of the door 90 so as to project below the bottom of the door and links connecting the hinge pieces on the support with those on the door. 95

13. The combination of a door, a support, hinge pieces fixed to the support, a hinge piece fixed to one edge of the door so as to project above the top of the door, a hinge 100 piece fixed to this edge of the door so as to project below the bottom of the door and links connecting the hinge pieces on the support with those on the door, the length of these links being equal to approximately 105 one half the width of the door.

14. The combination of a door, a support, a hinge piece fixed to said support, a second hinge piece fixed to one edge of the door and a link connecting these hinge pieces and means including lugs carried by the door 110 for causing the opposite edge of the door to follow a certain path when the door is swung open.

15. The combination of a door, a support, a hinge piece fixed to said support, a second hinge piece fixed to one edge of the door, a link connecting these hinge pieces, the length of this link being less than the width 115 of the door, and means including lugs carried by the door near the other edge thereof adapted to cooperate with slots to cause this other edge to follow a certain path when the door is swung open.

16. The combination of a door, a support, a hinge piece fixed to said support, a second hinge piece fixed to one edge of the door and a link connecting these hinge pieces, the length of this link being equal to substantially 120 one half the width of the door, and 125

means other than the means carried by the support for causing the opposite edge of the door to follow a certain path when the door is swung open.

- 5 17. The combination of a door, a door casing having a slot in the top thereof and a second slot in the bottom thereof, a support, hinge pieces fixed to the support, a hinge piece fixed to one edge of the door so as to project above the top of the door, a hinge piece fixed to this edge of the door so as to project below the bottom of the door, links connecting the hinge pieces on the support with those on the door, the length of these links being equal to approximately one half the width of the door, brackets fixed to the door at the upper and lower corners thereof

opposite this edge of the door, the said brackets having lugs thereon projecting into the slots in the door casing. 20

18. The combination of a door, a support, means hinged to the support and to one edge of the door for causing this edge of the door to swing out away from the support when the door is opened, means other than the means carried by the support for causing the opposite edge of the door to follow a certain path when the door is swung open and means for locking the hinged edge of the door. 25 30

In testimony whereof I affix my signature.

IRWIN CHASE.
